SAFETY RAZOR

Joseph F. C. Przybysz, South Bend, Ind.

Application October 18, 1943, Serial No. 506,691

10 Claims. (Cl. 30—70)

This invention relates to improvements in safety razors.

The primary object of the invention is to provide a novel, simple and inexpensive razor of high precision.

A further object is to provide a razor of this character wherein a thin blade is held flat to provide straight cutting edges and avoid waviness or distortion of cutting edges.

A further object is to provide a razor with novel means for engaging a blade both centrally and peripherally to accurately center the blade.

A further object is to provide a razor having inner and outer blade-clamping plates, wherein a guard bar projects from the sides of and is carried by the outer plate in a manner to assist in centering of the blade and inner plate relative to the outer plate and to protect the edged portions of the blade.

A further object is to provide a razor with an improved safety factor.

A further object is to provide a razor which can be effectively cleaned, which will not cut or chafe the skin at any angle of attack, and which is sufficiently strong and solid to avoid breakage thereof or of its blade upon impact, as when dropped.

Other objects will be apparent from the description, drawing and appended claims.

In the drawing:

Fig. 1 is an end view of the assembled razor.

Fig. 2 is a transverse sectional view taken on line 2—2 of Fig. 3, and illustrating the relation of the blade to the outer plate.

Fig. 3 is an inner face view of the outer plate and a blade carried thereby.

Fig. 4 is a perspective view of the outer plate.

Fig. 5 is a side-edge view of the inner plate.

Fig. 6 is a face view of the blade-engaging surface of the inner plate.

Fig. 7 is an end-edge view of the inner plate.

Referring to the drawing, which illustrates the preferred embodiment of the invention, the numeral 10 designates the handle, 11 the inner plate, 12 the outer plate, and 13 the blade of the razor. Handle 10 is of any suitable size and shape and has an internally screw threaded bore in one end portion opening at a flat end face normally lying in plane 14.

The outer plate 12 is flat and has an inner blade-engaging face 15 which is ground, lapped or otherwise processed to render it flat and smooth within small tolerances. Plate 12 has parallel elongated slots 16 formed adjacent its opposite sides. The ends of said slots are equi-

spaced from the ends of the plate and communicate with short inwardly directed transverse cuts 17. Slots 16 and cuts 17 define a longitudinal guard bar 18 and end bars 19. End bars 19 are bent sharply at the inner ends of the cuts 17 to define bend lines 20 spaced inwardly relative to longitudinal edges of the flat central plate portion. As here shown, bars 19 are bent at approximately 45 degree angles to the central flat portion of plate 12, but this angle is not critical and may be varied over a wide range. The outer edges of guard bars 18 are rounded, and the inner faces 21 thereof preferably extend substantially perpendicular to face 15, and are spaced apart a distance slightly greater than the width of blade 13. The outer edges 22 of the center flat portion of the plate are beveled to lie flush with the outer faces of bars 19 as shown in Fig. 2. A stud 23 projects centrally from the inner face of plate 12, the outer end thereof being a screw threaded for detachable connection with handle 10, and the inner end portion 24 being slightly tapered or frusto-conical.

The inner plate 11 is of a length slightly greater than the length of plate 12, and of a width equal to the width of the flat central portion of plate 12. Plate 11 has a central aperture 25, adapted to have a free centering fit around stud 23. The inner face 26 of plate 11 is ground, lapped or otherwise processed to make it smooth and flat. The outer face preferably tapers at 27 towards its side edges. The end edges 28 of plate 11 are preferably slightly beveled outwardly from face 26 to the outer face. Each corner of plate 11 is cut-away on a bevel 29, said bevel faces fitting snugly against the inner inclined edges of bars 19 to accurately position said inner plate relative to the outer plate when said plates are assembled.

The blade 13 is of the flat thin type having a central hole 30 of a size to engage the beveled portion 24 of stud 23 with a snug but free centering fit. The blade is of a length slightly greater than outer plate 12 and substantially equal to the length of inner plate 11. The width of the blade is greater than the width of plate 11 and of the central portion of plate 12, and less than the spacing between inner faces 21 of guard bars 18. The parts are preferably so proportioned that the opposite longitudinal cutting edges project beyond the planes of the outer inclined faces of bars 18 and 19 of plate 12 a few thousandths of an inch only, preferably not greatly in excess of .010 of an inch. The corners of the blade are notched to permit the blade

to fit between bars 19, and the longitudinal spacing between notches is preferably only a few thousandths of an inch less than the longitudinal spacing between the bars 19 at the opposite ends of each guard bar 18. This permits free fitting of the blade to the outer plate, and removal therefrom, but limits play of the blade relative to plate 12 for centering purposes. Obviously this feature insures maintenance of parallelism between the cutting edges and the guard bars, and a precision assembly of parts without requiring special care in the assembly operation.

The parts are assembled with blade 13 between and in full face engagement with faces 15 and 26 of plates 12 and 11, respectively. Thus the blade is fully supported and held rigid by said plates, except at its cutting edges and at its end margins. The support is sufficient to prevent distortion or waviness of the cutting edges. No special care in assembly is required because of the self-fitting function served by the inclined end bars 19. Hence, assembly is simple, quick and accurate, and entails mere putting of the parts together in proper relation and tightening of the handle on stud 23 to effect a clamping of the blade between the plates. The relative lengths of the plates and the blade, together with bevel 28 of the inner plate, make dis-assembly or separation of parts easy.

The unitary elongated guard bars 18 and the elongated slots 16 serve several important purposes. The guard bar 18 smooths and stretches the skin ahead of the blade, completely avoiding formation of skin ridges, and the beveled edges 22 smooth the skin on the other side of the blade. Hence, the cutting edge, being parallel to said bar, has a uniform beard-cutting action upon a flat stretched area of skin at all times, and will not cut or chafe the skin. The bar also uniformly smooths and distributes the shaving cream ahead of the blade. Also, in view of the slight projection of the cutting edge beyond the plane of the outer inclined edges of bars 19, the skin cannot be cut, regardless of the angle at which the razor is held. This is in distinct contrast to conventional razors wherein the blade is flexed to present a small angle between the cutting edge and the path of movement when the razor is held in certain positions so that the skin can be cut when the razor is held at such angles if the razor is pressed against the skin beyond the critical point or if the plates are loose. Note also that the continuous character of the slot provides an open passage for full free access of water to wash the razor, and avoids small pockets in which the mixed cream and hair could find lodgment or which would make cleaning difficult. At the same time the groove can be made narrower than in previous razor constructions to increase the support for the blade.

The formation of the guard bar on the outer plate is also important for additional reasons. Thus, the corners of the blade at the ends of the cutting edges are protected by the inclined bars 19. This prevents the possibility that the user will cut or "nick" his skin on said corners if the razor should be used improperly or if the user's hand or arm should be unsteady or accidentally jogged or struck. Also, if the razor should be dropped, the bars 19 prevent the corners of the blade adjacent the cutting edge from being struck, and hence prevent breakage of the blade.

I claim:

1. A safety razor comprising a flat substantially rectangular blade notched at each corner

portion, an outer plate having a flat blade-engaging surface, inclined corner bars projecting from said plate, guard bars extending between the outer ends of said corner bars and spaced outwardly from said plate, an inner plate having a flat blade-engaging surface and corner notches fitting around said corner bars, and means for clamping said plates together, said inclined corner bars centering said blade and inner plate relative to said outer plate.

2. A safety razor comprising a blade, outer and inner blade-clamping plates, said outer plate having a longitudinal slot defining transverse corner bars bent angularly from said plate, and a guard bar spanning the outer ends of said corner bars, said blade and inner plate being notched at their corners, whereby their side portions fit between said inclined corner bars, and means for clamping said plates together.

3. A safety razor comprising an outer plate having a longitudinal slot defining a U-shaped guard projecting angularly outwardly therefrom, an inner plate, means for clamping said plates together, and a blade clamped between said plates and having an edged portion projecting laterally therefrom through said slot.

4. A safety razor comprising an outer plate having a pair of longitudinal slots defining opposed marginal U-shaped guards projecting angularly outwardly therefrom, an inner plate, means for clamping said plates together, a blade clamped between said plates and having opposed edged portions extending through said slots, said inner plate and blade being centered by engagement thereof with the angular end portions of said guards.

5. A safety razor comprising an outer plate having parallel longitudinal slots defining transverse corner bars bent angularly therefrom and guard bars spanning the outer ends of said corner bars at each side, an inner plate, a blade, and means clamping said blade between said plates, said inner plate and blade having portions fitting between and positioned by opposed corner bars.

6. A safety razor comprising an outer plate having parallel longitudinal slots defining transverse corner bars bent angularly therefrom and guard bars spanning the outer ends of said corner bars at each side, an inner plate, a blade, and means clamping said blade between said plates, said inner plate and blade being of lengths at least equal to the length of said outer plate and having corner notches defining portions fitting between the corner bars at opposite ends of each slot.

7. A safety razor comprising an outer plate having parallel longitudinal slots defining transverse corner bars bent angularly therefrom and guard bars spanning the outer ends of said corner bars at each side, an inner plate, a blade, and means clamping said blade between said plates, said blade being notched at its corners and having edged portions passing through said slot, said inner plate having beveled corner notches complementary to said corner bars.

8. A safety razor comprising an outer plate having parallel longitudinal slots defining transverse corner bars bent angularly therefrom and guard bars spanning the outer ends of said corner bars at each side, an inner plate, a blade, and means clamping said blade between said plates, said plates having flat blade-engaging faces and said blade being of a width to pass through said 75 slots.

9. A safety razor comprising an outer plate having parallel longitudinal slots defining transverse corner bars bent angularly therefrom and guard bars spanning the outer ends of said corner bars at each side, an inner plate, a blade, and means clamping said blade between said plates, said guard bars and the adjacent plate edges inwardly of said slots including coplanar outer surfaces, said blade passing through said slots with its cutting edges spaced between and substantially in the planes of said surfaces.

10. A safety razor comprising an outer plate,

a stud projecting perpendicularly from the center of said plate, bars projecting angularly and laterally from the plate at each corner thereof, longitudinal guard bars carried by the other ends of said corner bars, an inner plate, a blade, and means for clamping said plates together, said blade and inner plate each having a central opening fitting around said stud and recessed corners fitting said corner bars for accurate registration of said plates and blade.
